UNITED STATES PATENT OFFICE.

THOMAS ERNEST DAVIS, OF AUBURN, NEW YORK.

SERVING-TABLE.

1,021,454.

Specification of Letters Patent. Patented Mar. 26, 1912.

Application filed January 23, 1911. Serial No. 604,204.

To all whom it may concern:

Be it known that I, THOMAS E. DAVIS, a citizen of the United States, residing at Auburn, in the county of Cayuga and State 5 of New York, have invented certain new and useful Improvements in Serving-Tables, of which the following is a specification.

My invention relates to improvements in 10 automatic serving tables and the leading object of my invention is the provision of a table of this character which will operate with ease to present the food as desired and which will be of simple and inexpensive 15 construction and present an attractive and ornamental appearance.

To attain the desired object my invention consists of a table having spring means for 20 rotating the table to present the food as required and a brake or stopping device to retain the table in proper relation.

The invention also consists of a serving 25 table embodying novel features of construction and combination of parts substantially as disclosed herein.

Figure 1 represents a side elevation of my 30 complete table. Fig. 2 represents a vertical sectional view. Fig. 3 represents a detail view of one of the brake levers, and Fig. 4 represents a detail view of the pawl and 35 ratchet used in connection with the spring operating mechanism.

It will be understood that my table is 40 placed upon the usual tables employed in dining rooms and is constructed to receive the food to be served, and the device consists of the base or support A, from which rises the staff B having the extended portion C of reduced size. Pivoted or ful- 45 crumed at D upon the base are two hand levers E, formed with an arm F, terminating at their upper ends in a brake G, and having the lower forked end H which is pivoted at J, to the sliding collar K, which 50 collar is normally held down by the coiled spring L. The upper end of the spring L bears against the lower reduced end of the hollow cap M, which is mounted on the staff and has the reduced opening N, to 55 snugly fit upon the lower portion of the reduced extension of the staff, and the cap is further provided with a ball track O in which are the balls P, forming ball-bearings for the table Q of my device.

Secured to the table Q and surrounding

and projecting above the extended end of the staff is the barrel or sleeve R, carrying the cap S, adapted to form a bouquet holder, and to the upper end of the sleeve is secured the casing T, in which is mounted the stud 60 U, having a head V, for turning the stud, a ratchet wheel W, engaged and retained by the spring pawl X, and connected at its lower end to the spring Y, whose lower end is rigidly secured to the upper end of the 65 staff extension C.

In normal position the parts are in the 70 relation shown in Fig. 1 and the spring brakes engage the periphery or edge of the table and retain the table, now upon the bearing down of either of the levers the 75 brake is released from the table and said table turns under the impulse of the spring in the sleeve and brings the desired articles upon the table in reach of the person, as 80 will be apparent. It is simply necessary to keep the spring under the proper tension by winding it through the medium of the pawl and ratchet devices and the brake-mechanism will instantly release the device to al- 85 low the table to turn and will engage and retain the table in the desired position.

A serving table constructed according to 90 my invention will prove particularly desirable in cafés, dining rooms and restaurants 85 as it is an article of decorative appearance and would save a great amount of time and labor.

One of the most important features of my 95 table is the construction of the combination hand levers and brake, the hand lever being formed with a lower forked end connected with the sliding collar and having an integral arm carrying a brake, thus making a novel form of combined operating lever and brake which work together to produce the desired result.

I claim:

1. A serving table, consisting of a support, a staff rising therefrom and having a lower enlarged portion, a collar slidably mounted on the lower portion and having pivotally connected thereto the lower ends of a pair of levers, said levers being fulcrumed near their lower extremities upon the said support and having formed integral therewith a pair of brake arms extending upwardly and having a portion adapted to engage the edges of the table, said collar being normally retained in position 100 105 110

by a coiled spring interposed between the collar and a cap mounted in bearings contacting against the underface of the table and upon which the table revolves when one 5 of the levers is depressed, and means mounted in the upper reduced portion of the support for revolving said table when the brakes are released.

2. In a serving table, the combination of 10 a base, a standard rising therefrom, a cap mounted on the standard immediately below and contacting with the table whereby the table is revolved through the medium of a spring mounted in the upper reduced portion 15 of said standard, said spring having a pawl and ratchet mechanism for adjusting its tension, a spring mounted on said standard immediately below said cap, a collar slidably mounted on the lower portion of 20 said standard below said spring, and a series of hand levers fulcrumed on the base and pivotally connected to said sliding collar, said hand levers having brake arms formed integral therewith and extending 25 upwardly to engage the edges of the table, said brake arms being adapted to be re-

leased from engagement with the table upon the depression of either of the hand levers.

3. A serving table, consisting of a support, a staff rising therefrom, a table mounted on the support, a collar in the lower portion of said staff, a cap mounted thereabove, a spring interposed between said collar and cap, levers fulcrumed on the base and having their lower ends pivoted to the collar, 30 said levers having brake arms formed integral therewith, said brake arms having a portion adapted to engage the edge of the table, a spring mounted in the sleeve of the upper reduced portion of said staff for revolving the table upon the bearings in said cap when either of said hand levers is depressed and means for retaining said spring under tension, said means consisting of a pawl and ratchet mounted in the casing of 40 45 the upper reduced portion of the staff.

In testimony whereof I affix my signature, in presence of two witnesses.

THOMAS ERNEST DAVIS.
